UNITED STATES PATENT OFFICE.

JAMES A. HINSON, OF CHICAGO, ILLINOIS.

BUFFER FOR RAILWAY-CARS.

SPECIFICATION forming part of Letters Patent No. 638,244, dated December 5, 1899.

Application filed March 2, 1897. Renewed May 2, 1899. Serial No. 715,339. (No model.)

To all whom it may concern:

Be it known that I, JAMES A. HINSON, a citizen of the United States, residing at Chicago, in the county of Cook and State of Illinois, 5 have invented certain new and useful Improvements in Buffers for Railway-Cars; and I do hereby declare the following to be a full, clear, and exact description of the invention, such as will enable others skilled in the art to 10 which it appertains to make and use the same.

This invention relates to buffering devices for railroad-cars, and has for its object to provide a simple device of few parts adapted to maintain the buffer-plates of adjacent cars in contact at all times, both in buffing and pulling, and thus prevent persons getting caught between them and injured, and to take up lost motion; and it consists of the parts and combination of parts hereinafter described and 20 claimed.

In the accompanying drawings, forming a part of this specification, Figure 1 is a plan view of my invention arranged in position under the platform of a car, the flooring of 25 which being removed to show the same. Fig. 2 is a plan view of the front face of the buffer-plate. Fig. 3 is a longitudinal vertical section through the platform. Fig. 4 is a detail perspective view of the buffer-plate. Fig. 5 is a 30 plan view of the follower-plate. Fig. 6 is a detail section through the center of the yoke and the end of the bar J. Fig. 7 is a side elevation of the inner ends of the yoke-arms. Fig. 8 is a plan view of the inner ends of the yoke- 35 arms.

Similar letters refer to similar parts in all the views.

Referring to the drawings, A represents a car-platform, and B a buffer-plate arranged 40 across the end of the same in line with the end timber C, and D a horizontal plate secured to and resting on the upper edge of the plate B. The edge of the plate D is formed with a recess a, and the plate B is formed with 45 a corresponding projection b, which fits into said recess a and serves to strengthen the plate B and prevent it bending from the blows received in buffing, especially where it is used to receive the blows from the type of buffer- 50 head known as the "Miller," which is very narrow.

The buffer guide-rods E are connected to

plate B, so as to permit of a rocking movement of the plate by means of the bolts c, which also serve to connect or secure the 55 plate D to said plate B, which extend through vertical perforations in plate B, intersecting openings d, into which the ends of rods E extend, and through eyes formed in said rods, thus jointing the rods E to the plate B, so 60 that the latter may yield at either end. The guide-rods E extend through openings therefor in the end timbers C, and their rear portions are reduced to form shoulders e, against which one end of the spiral springs f, mounted on said rods, abut or bear, the other ends of said springs abutting against a collar g, loosely arranged on the rods E. The collars g are formed with a central ridge h, which fits in a recess or semicircular groove i, formed 70 in the edges or sides of the arms j j' of the yoke F, said arms being also formed with openings through which the ends of the rods E extend and which are secured against withdrawal by pins or keys k. The extreme ends 75 of the arms j j' extend into the grooved stops G, bolted to the side timbers H, and their rearward movement is limited thereby. The yoke is formed of the two arms j j', jointed or hinged together at their inner ends by a pin 80 I, which also serves to connect a bar J to the yoke, for a purpose to be explained hereinafter.

As shown in Fig. 7, the arm j' is formed circularly and perforated, as at n, to enter between the lugs or ears l and with shoulders o to engage the stops m, and thus limit the movement of the arms on the pin I. The arms j j' are formed on the curved lines shown, so as to present the convex bearing-surface p, 90 Fig. 1, and the concave bearing-surface q, and said arms extend through slotted openings r, formed therefor in the draft-timbers L. The openings r are provided with the wear-plates M, formed with the rounded ends s, 95 against which the concave surfaces q of the arms j j' bear, and the ends of the follower-plate N, which extend into the openings r, bear against the convex surfaces p of said arms. The follower-plate N is reduced at each end, 100 so as to form shoulders t, which fit against the draft-timbers and guide the plate in its movement. The follower-plate N is formed with a central opening u, into which the buffer-bar

O extends, the opposite end of said bar extending through an opening in the end timber of the platform and into position to be struck by the buffer-plate B while buffing, 5 and a shoulder v, formed on said bar O, bears against a small follower-plate P, arranged on said bar between said shoulder and the end of the buffing-spring Q, the other end of said spring Q bearing against the follower-plate 10 N. The springs f on the rods E are so compressed when the cars are coupled as to bring the buffer-plate B against the front end of the center buffer-bar O.

The bar J, hereinbefore mentioned as connected to the yoke F, is formed with a split and perforated end a', so as to embrace the jointed or hinged ends of the arms, and extends backwardly to the end of the draw-bar of the coupler, to which it is bolted, as at 15 b', or in any other suitable manner. The car-coupler R proper here shown may be of the usual or of any desired type or form and is connected in the usual manner with the draw-spring c' and follower-plates d', which are also 20 arranged so as to slide in the draw-bar guides bolted to the draw-bar timbers and form no 25 part of my present invention.

With the parts in the position shown in Fig. 1 any pull or forward strain on the coupler 30 draws the yoke bodily forward against the pressure of the springs f and Q, so that in starting a train the buffer-plates of adjacent cars are kept firmly together or in direct contact and closing the space which would otherwise be left between them. When the cars 35 are brought together in buffing, the buffer-plates are driven back and the side springs f compressed, the coupler being also driven back at the same time, causing the bar J to 40 draw back the center of the yoke F, thus throwing its arms forward and taking up lost motion and reducing the movement of the plates B; also, when the buffing is heavy the bar O compresses the spring Q and coming 45 in contact with the center of the yoke transmits, through the bar J, the strain or a portion of the strain imparted thereto to the draw-spring c', thus bringing into action all four springs to resist the strain.

Owing to the fact that the yoke-arms are 50 limited by the shoulders o on arm j' engaging the stop m on arm j the yoke will be bodily moved forward by the bar J when the coupler is pulled forward, so that, it will be observed, 55 buffing on the coupler causes the bar J to draw the inner jointed ends of the arms j j'

backward, which causes the outer ends of said arms to be thrown forward, thus holding the plates or reducing the lost motion which would otherwise occur between the buffing-plates B. The follower-plate N with the aid of the spring Q prevents the yoke assuming angles when rounding curves, as happens with all buffing devices with which I am familiar, and which angular positions are maintained both in the yoke and the buffer-plates after the train gets straightened out, since no provision has been made to cause them to resume their proper position.

Having thus described my invention, what 70 I claim as new, and desire to secure by Letters Patent, is—

1. The combination, in a buffing device for railway-cars, of a centrally-jointed yoke connected to the ends of the buffer-plate, and a 75 bar connected to said yoke and the draw-bar of the coupler, substantially as described.

2. The combination, in a buffing device for railway-cars, of a yoke, comprising two arms jointed together, one of said arms being provided with a stop and the other with a shoulder to limit the movement, guide-rods connecting said arms and the buffer-plate, springs arranged on said guide-rods, a central buffing-bar, a follower-plate, a spring arranged 85 on said buffing-bar, and a bar connecting the yoke and the draw-bar of the coupler, substantially as described.

3. The combination, in a buffing device for railway-cars, of a vertical buffer-plate, a horizontal plate, guide-rods loosely jointed to said vertical plate, and a jointed yoke having its arms connected to said rods substantially as described.

4. The combination in a buffing device, of 95 the buffer-plate, guide-rods loosely pivoted thereto, springs for said rods, a yoke consisting of two arms pivoted together at one end, guiding-stops for the ends of said arms, bearings for said arms secured in the draw-timbers, a follower-plate bearing against said yoke, a buffing-bar, a spring for said bar, and a bar connecting the center of said yoke and the draw-bar of the coupler, substantially as 100 described.

In testimony whereof I affix my signature in presence of two witnesses.

JAMES A. HINSON.
